UNITED STATES PATENT OFFICE.

KENNETH HOWIE, OF NORRISTOWN, PENNSYLVANIA, ASSIGNOR TO WILDMAN MFG. CO., OF NORRISTOWN, PENNSYLVANIA, A CORPORATION OF PENNSYLVANIA.

FULL-FASHIONED-KNITTING MACHINE.

Application filed May 26, 1927. Serial No. 194,324.

One object of this invention is to provide a frame structure for full fashioned knitting machines of the Cotton type having the characteristic that it presents a unitary construction in the sense that all the sections or heads are supported on and united together by a sill or base which rests upon the floor.

Machines of the full fashioned hosiery type are made up of a large number of sections or heads, sometimes twenty-four. These sections are arranged side by side in a row and the standards or cross frames supporting these sections are individually supported on the floor.

Machines of this type have elements extending the entire length of the machine, say forty-two feet, such as the thread carrier bars, and the slur cock carrying bar. Certain parts reciprocate vertically, such as the needle bars. Certain parts reciprocate in a direction transversely of the machine, such as the dividers and operating mechanism, including the catch bar. By reason of these various reciprocating parts and the different direction of movement, considerable vibration develops in machines as now constructed.

One object of the present invention is to eliminate this vibration. For this purpose I employ a sill or platform upon which the different sections or heads of the machine are mounted so that all are bound together in a structure which is of unitary character, both longitudinally and transversely.

Other objects of the invention will appear from the following description taken in connection with the drawings forming a part of this specification.

40 In the drawings:

Figure 1 is a diagrammatic rear view of a full fashioned knitting machine of the Cotton type.

Fig. 2 is a perspective view of a portion of the base or sill member.

Fig. 3 is a plan view of one of the sections of the base or sill member.

Fig. 4 is a cross section of Fig. 3 on line 4-4.

50 Fig. 5 shows the base in end view with a standard thereon.

Fig. 6 is a detail view, and

Fig. 7 is a longitudinal section showing two sections of the base bolted together.

55 In these drawings 1 indicates standards

disposed at regular intervals along the machine. Said standards in the ordinary type of these machines are provided with legs having feet which rest upon the floor.

These standards support the working parts, including the various knitting organizations, shafting cams, etc.

With my improvement, instead of mounting these standards or cross frames individually upon the floor of the factory, I provide a unitary structure both lengthwise and laterally by a base frame extending the entire length of the machine and providing a substantially integral structure both lengthwise and crosswise, and upon this base frame the cross frames or standards 1 are mounted. These standards or cross frames, together with the base which supports them, provide a structure of the same height as machines heretofore employed, so that the relation of the knitting elements, the parts to be manipulated by the attendant and the position of the goods as produced by the machine relative to the operator, is not altered and the operator can perform all the operations necessary with the same degree of convenience as heretofore. For this purpose the standards are formed without the usual length of supporting legs individual thereto, the said base frame taking the place of the extent of leg heretofore used.

The base frame is of cast iron. It is composed of sections such as 4^a, 4^b, 4^c, 4^d, arranged end to end and bolted together. The upper part of this frame is planed along its front and back rails to leave two upstanding ribs 5, 5, which provides for the true setting of the standards 1 thereon. Each base section is provided with a cross bar as at 6 at each end, and the longer sections, for instance, as 4^b, are provided with a cross bar 7 intermediate of its length, all of these parts, front and back rails and cross bars of each section, being cast in one piece.

100 The base sections are each provided with a number of feet, as shown at 8. These are braced by vertical webs 9 cast with the rails of the base and these foot portions are connected with the downwardly extending portions at 10 of the front and rear walls 11, 12 forming parts of the front and rear frame bars of the base. The standards 1 are placed upon the planed upper surfaces or ribs 5, 5, of the base and are thus accu- 105 110

rately located in respect to each other, so that the bearings carried thereby will be in accurate alignment throughout the whole series of standards of which in the present machine there may be, say 15. These standards are bolted to the planed surfaces or ribs of the front and back and in accurately predetermined positions, and preferably each standard's position is adjacent one of the foot portions of the base, so that the weight of the standard and the portions of the machine immediately supported by said frame is taken by the base frame at the points where the corresponding foot portion of the front and back bars or rails of said base frame rest upon the floor, whereby a stiff, strong support is afforded for the whole machine, and particularly those parts of the base frame which receive the immediate downward thrust of the standards. The foot portions of the standards are formed with lugs 5^a embracing the ribs 5 as shown in Fig. 5. This construction prevents the standards from being twisted out of their prescribed relation to the other parts of the machine.

As is well known to those skilled in setting up and operating full fashioned hosiery machines of the well known "Cotton" type, it is necessary to true up the standards independently in the case of an uneven floor. Each standard transmits its stresses through the individual truing-up shim or block to the floor. With my construction the standards individually need no truing up, as they are firmly bolted down to the accurately planed upper surface or ribs of the base frame. The base frame or sill is trued up as a whole by inserting shims under the feet thereof, if needed, and the weight, stresses and strains are transmitted from the standards to the base frame as a whole and are distributed through the said base frame which is common to all the standards.

This base frame also affords a support for the pivot bearing of the main traverse lever 13, which gives reciprocating movement to those parts of the machine which move back and forth lengthwise thereof. This traversing lever is operated by well known mechanism and connected with the parts it is to move by a link 14. Its pivot bearing consists of a pin 15 mounted in a bracket 16 supported by the rear rail or bar of the main base frame or sill.

In the present improvement the thrust from this traversing lever is taken by the pivot and is distributed through the supporting bracket into the rigid base frame which sets low in respect to the rest of the machine, is supported by the floor, and being massive in form, will sustain the thrust effectually and entirely independent of the standards which must, for perfect working of the machine, hold their various bearings

in alignment with similar bearings on the other standards throughout the machine.

The base frame or platform is made in sections for convenience in handling. They are bolted together through their end walls or flanges at 17. Each section is of rugged form composed of front and back bars, angular in cross section, said bars being connected with integral cross bars at the ends of the sections. Where the section forms the end one of the base the cross bar at the extreme outer end is of angle form in cross section, whereas the cross bar at the inner end of the section is a plain horizontal bar. Where the inner ends of two sections meet, their cross bars are adjacent.

The base frame is of importance in holding the machine against lateral misalignment of the parts, as each standard is rigidly maintained in its prescribed position and can have no displacement in a direction transversely of the machine. This is not true where each standard or cross frame is individually secured to the floor of the factory.

I claim:

1. In a full fashioned hosiery machine of the type made up of a plurality of sections or units arranged side by side, and comprising standards spaced apart along said machine, for supporting the various parts thereof, and means for binding the units together into one unitary structure both lengthwise and crosswise of the machine, comprising a base frame of substantial solidity and weight to which the standards are connected at their lower ends, and upon which they are supported, the combined height of said base frame and standards being substantially the same as the normal height of standards in prior forms of this type of machine, and the horizontal plane in which the lower ends of the standards lie being elevated in respect to the floor and comparatively close to the plane in which the working parts of the machine operate.

2. In combination in a full fashioned hosiery machine, made up of a plurality of units side by side, and having standards spaced apart along the machine, a base member to rest on the floor having a pair of ribs at the front and a pair of ribs at the rear extending lengthwise of said frame, the said standard having foot portions resting on and embracing said ribs and bolted to the frame, substantially as described.

3. A full fashioned hosiery machine according to claim 1 in which a working part of the machine is supported on the said base platform, substantially as described.

4. A full fashioned hosiery machine according to claim 1 in which the base platform comprises front and back rails which are planed on their upper surface to afford seat spaces for the standards to accurately

align the same, substantially as described.

5. A full fashioned machine according to claim 1 in which the base platform has feet spaced apart along the same to rest upon the 5 floor, substantially as described.

6. A full fashioned machine according to claim 1 in which the base frame or platform is composed of an open frame having front and rear bars integrally connected by cross 10 bar portions, substantially as described.

7. A full fashioned machine according to claim 1 in which the platform has foot portions to rest on the floor adjacent the points where the standards are supported on the 15 said platform.

8. A full fashioned machine according to

claim 1 in which the platform is made up of sections disposed in the same horizontal plane, each section supporting a number of sections of the machine, said platform sections being rigidly connected together. 20

9. A full fashioning hosiery machine according to claim 1, having a traversing lever to give reciprocating movement to working parts of the machine and in which the traversing lever is pivotally mounted on said base platform or sill, substantially as described. 25

In testimony whereof, I affix my signature.

KENNETH HOWIE.
